MODULATED CARRIER WAVE
TRANSMITTERWilliam Stuart Leader Tringham, Puttenham,
Guildford, England, assignor to Radio Corpora-
tion of America, a corporation of DelawareApplication October 10, 1936, Serial No. 104,957
In Great Britain October 24, 1935

2 Claims. (Cl. 179—171.5)

This invention, which is for improvements in or modifications of the invention contained in United States application, Serial No. 753,291, filed November 15, 1934, by W. S. L. Tringham, which issued on April 13, 1937, as Patent No. 2,076,685, relates to modulated carrier wave transmitters and apparatus for use therewith. More specifically the invention relates to what may be termed "modulation monitoring" arrangements for use in connection with radio and like transmitters and whereby the correctness of the modulation at different stages of the transmitter may be checked from time to time and during operation of the said transmitter.

Though not exclusively limited in its application thereto, the invention is primarily intended for "monitoring" television transmitters.

According to the parent invention a modulation monitoring installation, for use for the purpose specified, comprises a cathode ray tube, means for deriving from a plurality of stages of the transmitter to be monitored potentials which should be like functions of the degree of modulation, and switching means or its equivalent whereby any of the potentials so derived may be applied to deflect the ray in the cathode ray tube, the deflection of the ray thus obtained serving as an informative indication of the correctness or otherwise of operation of the transmitter.

It frequently happens that the monitoring indication is required to be given at some point, hereinafter to be termed the "control desk", which is some appreciable distance from the transmitting apparatus proper, the various transmitter and modulating controls being generally arranged at the control desk.

It is also desirable, in carrying out the invention contained in the parent patent, to be able to employ as the monitoring indicator a cathode ray tube of small sensitivity. The present invention enables the cathode ray tube indicator to be located at the control desk and well away from the transmitting apparatus proper without difficulties due to the wide range of frequencies required to be handled, in a television transmitter in particular these frequencies may occupy a very wide range, and furthermore facilitates the satisfactory use of a cathode ray tube of low sensitivity.

According to the main feature of this invention there is provided between the switching means and the cathode ray tube of an installation in accordance with the parent invention an amplifier which serves to amplify any of the

potentials which may be derived from the different stages of the transmitter and passed on to the cathode ray tube.

According to another feature of this invention, a rectifier provided for rectifying modulated carrier wave energy taken from the transmitter and to be fed to the switching means and thence to the cathode ray tube, is located adjacent said switching means, i. e., at or near the control desk.

The invention is illustrated in the accompanying drawing in which Figure 1 shows diagrammatically an embodiment for use in an installation wherein provision is required to be made for monitoring the output from three different stages of a transmitter, namely a sub-modulator stage, a modulator stage, and a high frequency modulated amplifier stage. Figures 2 and 3 show a preferred form of switch which may be used in place of that shown in Figure 1.

Referring to Figure 1 there is employed as switching means a rotary switch SW like that illustrated in the drawing accompanying the parent specification and having twelve contacts arranged in a circle and two mutually perpendicular contact arms A1, A2, each adapted to bridge diametrically opposite contacts, said arms being arranged to be rotated together. The fixed contacts in this switch will be designated in the same way as in the parent specification, i. e., they will be numbered clockwise from 1 to 12, contact No. 12 being taken as the contact at "12 o'clock". Contacts 12, 1 and 2 are connected together and through a suitable bias battery GB to the input grid G of an amplifier comprising any desired number of amplifying stages arranged to maintain the direct current component during amplification and whose output circuit contains a resistance across which potentials are tapped off to the deflecting plates of the cathode ray tube indicator. In Fig. 1 only one valve V is shown, the resistance, across which potentials are taken off to the deflector plates of the tube, not shown, being marked R. In place of using a battery GB any other suitable bias source, e. g., a rectifier arrangement, could, of course, be employed.

Contacts 3, 4, and 5 are connected together and to the cathode C of the valve V. A grid resistance GL is connected directly between contacts 2 and contact 3. Contact 6 is connected to earth through a resistance R1 and also through a suitable high frequency inductance choke CH to the cathode C1 of a diode VI whose anode A1 is connected to earth through a parallel tuned circuit L2, K2, shunted by a resistance R2. Contact 65

1 is connected through a suitable cable HFC, preferably a high frequency cable, to a variable tapping T upon the anode resistance AR of the sub-modulator stage, not shown, to be monitored. 5 This cable of course extends from the control desk, indicated by the broken line, to the point where the rest of the transmitter is located. Contacts 8, 9, and 10 are connected together and to earth. Contact 11 is connected through 10 a second cable HFC1, preferably also a high frequency cable, to a variable tapping T1 upon the anode resistance AR1 of the modulator stage to be monitored. Modulated high frequency output is taken, for example as shown, via a condenser K, from the "live" member of the modulated output feeder F of the transmitter, not shown, and the energy thus taken is fed through 15 a high frequency cable HFC2 to an adjustable tapping T2 upon the inductance in the parallel tuned circuit L2 K2 in the anode circuit of the diode V1. This parallel tuned circuit is tuned to the working frequency and the resistance R2 is made sufficient to maintain the frequency response reasonably flat up to about 3 megacycles. 20 Preferably the three cables used have outer screens which are earthed and the arrangement is such in each case that the frequency response obtained at the control desk ends of the feeders is reasonably flat up to about 3 megacycles, for 25 the case of modern high definition television. 30 It is obviously not essential to take off the monitoring voltages from intermediate tappings T and T1 upon the anode resistance AR and AR1 as illustrated and in some cases it may be found better to take off voltage from the "live" 35 end of resistance AR and/or from the "live" end of resistance AR1 instead of using the intermediate tap method.

Where direct connection to the "live" end of an anode resistance is employed, suitable series 40 resistance should, of course, be inserted in the appropriate lead by which the voltage in question is taken in order to reduce the said voltage to the level required. This method of taking off monitoring voltage is most likely to be preferable in the case of the modulator resistance AR1. It is common practice to house the modulator and modulated amplifier in different cubicles and to connect the two by means of a high 45 frequency feeder. If this feeder is of any substantial length the frequency response of the modulation signals will be different according to which end of the feeder it is measured at. Obviously it is preferable to monitor at the input to the modulated amplifier. 50

It is not necessary to take the energy to the rectifier V1 from the feeder F in the precise manner shown. For example, the "live" member 55 of the feeder F may be connected to one terminal of a condenser of, say 10 micro-micro-farads, whose other terminal is earthed through a low resistance of, say 2 ohms, the outer feeder conductor is usually earthed, the "live" end of this resistance being taken to the rectifier. Such a 60 circuit will give a satisfactorily level response for the monitoring system. A similar circuit may also be used to take off modulated high frequency from the feeder to a rectifier feeding into a local, monitoring, television reproducing system, not shown, so as to enable the quality of the pictures transmitted to be observed at the monitoring station. A defect of this type of circuit wherein a capacity of about 10 micro-micro-farads in series with a low resistance is 65 shunted across the feeder is that this shunt cir-

cuit will, unless its point of connection be carefully chosen, have a marked, undesired effect upon the input impedance of the said feeder. Where such a circuit is employed, therefore, the shunt circuit is, according to a subordinate feature of the invention, connected across the feeder at a point substantially $\frac{1}{3}$ of the working wave length from the transmitter and of said feeder. When so connected the shunt circuit acts as an impedance transformer, a capacity of 10 micro-micro-farads at this point will transform an input impedance of about 70 ohms into one of about 61 ohms, and thus serves a dual purpose, for an impedance transformer is often required at this point in a television transmitter 15 system—i. e., near the transmitter end of the aerial feeder so that a certain amount of loading from the aerial may be thrown into the anode circuit of the final amplifier of the transmitter without having to couple said anode circuit so closely to the input coil of the feeder as to make the said anode circuit difficult to tune. The shunt circuit which serves the dual purpose referred to, should, of course, be as free from inductance as possible. 20

Figures 2 and 3 show a preferred form of rotary cam operated switch which may be substituted for the switch SW of Figure 1. Figure 2 is a schematic end view of the switch, with the operating knob removed, and Figure 3 is a schematic elevation. The operating knob O is mounted on the end of a shaft S on which cams CM1, CM2, CM3 of insulating material are keyed. The cams are staggered or phase displaced in a rotary sense so that, as the knob O is rotated, each cam protuberance points upwards in turn. Each cam operates two pairs of contacts of telephone type in a manner which will be obvious from the figure. The contacts in Fig. 3 are given references corresponding to those of switch SW 40 of Fig. 1 and the switch of Fig. 3 is shown in the position corresponding to that in which the switch SW of Fig. 1 is shown. By rotating knob O through 120° from the position shown in Fig. 3 contacts 1 and 7 and 4 and 11 will be closed 45 and the other contacts opened.

It will be seen that with arrangements as above described a common amplifier is employed for all the energies to be fed to the cathode ray tube and in practice the deflecting voltages 50 available at the tube will commonly be of the order of 150 volts or more, assuming the valve to give a voltage magnification of about 3, so that with two thousand volts on the electron gun anode of the tube it will be possible with present 55 day practice to obtain on the fluorescent screen of the tube, an image which is easily visible in daylight with a deflection of nearly 30 millimetres.

The specific embodiments above described and illustrated are suitable for a case where the A. C. and D. C. voltages with respect to earth are opposite at the modulator monitoring point as compared to the sub-modulator monitoring point. In some cases, however, the D. C. voltages may be in the same sense but the A. C. voltages in opposite sense. In such a case the above described switching arrangements could be employed but a suitable bias source should be connected in series with one monitoring cable. 70

Having described my invention, what I claim as new and desire to secure by Letters Patent is:

1. A modulation monitoring installation used with a modulated radio transmitter, wherein is provided a plurality of stages, comprising a cath-

ode ray oscillograph, means for deriving from a plurality of stages of the transmitter monitoring potentials which are representative of the degree of modulation, a single rotary cam-operated switch for selecting one of the potentials so derived, a wide frequency band amplifier connected between the switch and the cathode ray oscillograph and a rectifier having a damped resonant input circuit interposed between one of the plurality of stages and the switch.

2. A modulation monitoring installation used with a modulated radio transmitter, wherein is provided a plurality of stages, comprising a cathode ray oscillograph, means for deriving from a plurality of stages of the transmitter monitoring

potentials which are representative of the degree of modulation, a single rotary cam-operated switch for selecting one of the potentials so derived, a wide frequency band amplifier connected between the switch and the cathode ray oscillograph, a rectifier having a damped resonant input circuit, said rectifier being connected to said switch, a concentric cable feeder, a serially connected resistance and capacitor connected across one-eighth of the working wave length of the feeder, and connections from the serially connected resistor and capacitor to the damped input circuit of said rectifier.
